UNITED STATES PATENT OFFICE.

CHARLES W. GLIDDEN, OF LYNN, ASSIGNOR TO THE MCKAY & BIGELOW
HEELING MACHINE ASSOCIATION, OF BOSTON, MASSACHUSETTS.

HEELING-MACHINE.

SPECIFICATION forming part of Letters Patent No. 374,894, dated December 13, 1887.

Application filed June 23, 1886. Serial No. 205,991. (No model.)

To all whom it may concern:

Be it known that I, CHARLES W. GLIDDEN, of Lynn, county of Essex, and State of Massachusetts, have invented an Improvement in

5 Heeling-Machines, of which the following description, in connection with the accompanying drawings, is a specification, like letters on the drawings representing like parts.

This invention in heeling-machines has for 10 its object to simplify and improve the mechanism for automatically transferring the top lifts into position between the top lift plate and the end of the heel of the shoe upon which the top lift is to be nailed or spanked.

15 In the machine herein to be described the top lifts are taken automatically from the hopper by means of jaws mounted upon a horizontally-reciprocating slide-bar, the said jaws having co-operating with them a carriage, 20 whereby the jaws are opened and closed automatically at the proper times to receive between them a top-lift, the slide-bar being then moved forward to place the top lift in position to be attached to the heel. The slide-bar and 25 jaws have co-operating with them an auxiliary slide, which receives upon it the top lift until at or about the time that it is being passed over the top-lift plate, at which time the end of the auxiliary slide-bar meets the nail-box

30 or a part thereof, and the movement of the said plate is stopped while the slide-bar and jaws continue in their forward movement, the said auxiliary slide being connected with the main slide-bar frictionally. I have also con-

35 nected the last-holding spindle with the walking-beam by means of devices, as will be hereinafter described, whereby the said spindle is adapted to yield slightly in a vertical position to compensate for ordinary variations in the

40 thickness of heels and top lifts. I have provided the post of the nail-box within the die-bed spindle with a notch, with which I have combined a latch or holder to prevent the nail-box from rising, as will be described. I have

45 also provided the die-bed spindle with a dash-pot to act as a cushion. I have also provided novel mechanism, which will be hereinafter described, for automatically raising and lowering the die-bed spindle at predetermined in-

50 tervals.

The particular features in which my invention consists will be hereinafter described, and fully specified in the claims at the end of this specification.

Figure 1 is a side elevation, with the framework partially broken out, of a heeling-machine embodying my invention. Fig. 2 is a detail showing the lifting device for the hook which holds in its extreme positions the toggle-joint for operating the walking-beam. Fig. 55 2^a is a detail of the cam-hub, to be described. Fig. 3 is a left-hand elevation of Fig. 1, or a front view of the machine. Figs. 3^a and 3^b show in sectional detail parts of the die-bed spindle, the post of the nail-box, and latch to 60 hold it; Fig. 3^c, a section of the dash-pot in the line z, Fig. 3. Fig. 4 is a section in the line x x, Fig. 1, looking down, the parts being 65 enlarged, the shafts being in elevation. Fig. 5 is a partial section in the line x^a, Fig. 6, 70 showing cams upon one of the shafts, the sleeve on the said shaft being partially broken out to show the spline and groove connecting the sleeve and shaft. Fig. 6 is a section of Fig. 5 in the dotted line x^b. Fig. 7 is a section of 75 Fig. 5 in the dotted line x^c. Figs. 7^a and 7^b are respectively a side elevation and top view of the lever employed to act upon the pressure-rod and lower the die-bed spindle. Fig. 8 is a plan view, partially in section, showing 80 the top-lift carrier and means for operating its jaws. Fig. 8^a is a view similar to Fig. 8, but showing the parts in different positions. Fig. 9 is a section of Fig. 8 in the line x^d. Fig. 10 is a section of Fig. 8 in the line x^e. Fig. 11 85 is a section of Fig. 8 in the line x^f; Fig. 11^a, a section of Fig. 8 in the dotted line x^g. Fig. 12 is a detail looking at Fig. 8 in the direction of the arrow 2 thereon. Fig. 13 is a vertical section showing the upper end of the spindle- 90 working screw and means for connecting it with the walking-beam. Fig. 13^a is a side elevation of the slide-bar of the top-lift carrier and some of its attached parts, the jaws or levers being omitted; Fig. 13^b, a side elevation 95 and plan of the carriage removed from the slide-bar. Figs. 14 and 15 are views in elevation and section of the mechanism for applying paste or glue to the top lift as it is being applied. Fig. 16 shows a section and under 100

side view of the top-lift plate and its swing-pin and spring. Fig. 17 is a detail showing the cam which operates the top-lift carrier. Fig. 18 is a detail in top view of the top-lift 5 hopper; and Fig. 19 is a side elevation of Fig. 18, one arm of the plate f^4 being broken off.

The frame-work A, of proper shape to sustain the working parts, is provided with a walking-beam, A', to move vertically a last-10 holding slide, A². The walking-beam is operated by a toggle-joint composed of links A³ A⁴, the link A⁴ being connected with a rock-shaft, A⁵, having on it a cam, A⁶, which receives a roll at the upper end of a link, A⁷, 15 jointed to a lever, A⁸, pivoted at A⁹, movement of the lever and link causing the roll of the link A⁷ within the cam A⁶ to move the toggle-joint in one and then in the other direction. The die-bed spindle B, held in guides B', has 20 at its upper end the usual trimming-lever, B², and above it, supported in well-known manner, is the usual nail-box, B³, provided with a top-lift plate, g².

Power is applied to the machine by means 25 of a belt on a pulley, B⁴, fast on the driving-shaft B⁶. At one side of the fast pulley is a loose pulley, B⁵. The shaft B⁶ has fast upon it two pinions, D⁷ and B⁷. The pinion B⁷ engages a toothed gear, B⁸, located at the right-30 hand side of the machine, but loose on a shaft, B⁹, having attached to it at one end a dog-carrier, C, provided with a dog, 2, controlled by a dog-shoe, C', on a slide-bar, C².

The dog 2 is at times made to engage the internal teeth of the continuously-driven loose wheel B⁸, and during such engagement the shaft B⁹ is rotated to move the lever C³, (see Fig. 3,) which reciprocates the carriage C⁴ on the way 3, attached to the frame-work, the 40 said carriage having attached to it a chain, C⁵, extended over the sprocket-wheel C⁶, which, through a cross-head, C⁷, and pins C⁸, actuates the trimming-lever B², the said chain also passing over a loose sheave, C⁹, mounted on a stud 45 at the back part of the frame-work. The die-bed spindle has connected with it a link, D, forming part of a toggle-joint, the other link, D', thereof having a fixed fulcrum, D².

The center pin, D³, of the toggle-joint has 50 connected with it a presser-rod, D⁴, having a shoulder, (shown by dotted lines, Fig. 1,) which at proper times is struck by a crank, D⁵, (shown by dotted lines in Fig. 1 and full lines, Fig. 4,) forming part of the crank-shaft D⁶, the said 55 crank and rod starting in usual manner the toggle to lift the die-bed spindle B at the proper times, as when the heel is being nailed upon the shoe and when the top lift is being spanked upon the projecting ends of the nails partially 60 driven into the heel, the shoe being at such times upon a last applied to the last-holding slide A² in usual manner.

The parts so far described are in common 65 use in the so-called McKay and Bigelow heel nailing and trimming machine, so that their operation need not be herein more fully set forth. The machine alluded to has been

selected as one upon which to apply my improvements, now to be described, the same consisting, essentially, in mechanism whereby 70 the top lifts may be automatically taken from a pile and be fed into position to be spanked upon the top-lift end of the heel.

My invention has also for its object to increase the speed of the working parts.

The pinion D⁷, (see Fig. 3,) fast, as stated, on the driving-shaft B⁶, engages a toothed gear, D⁸, fast on and drives the shaft D⁹ continuously. The shaft D⁹ has fast upon it a pinion, D¹⁰, which engages and rotates continuously 80 a toothed gear, D¹¹, loose on the shaft 4. The shaft 4 at one end has attached to it an arm, 7, provided with a dog, 6, controlled by a stop shoe, E, attached to a sliding rod, E'. The dog 6, when released from the stop- 85 shoe, engages the internal teeth, 5, of the continuously-rotating gear D¹¹, which latter, through the dog, causes the shaft 4 to be rotated in unison with it. The slide-rod E', carrying the stop-shoe E, is reciprocated at 90 the proper time by a forked lever, E², pivoted upon a bolt, 77, (see Fig. 1,) the upper end of the said lever having a roll or wheel, 108, which is acted upon by a cam-hub, 8, loose on a pin, 9, held fast in a bracket, 10, the said cam having an arm, 12, which is provided with a pin, 13, that by link 14 is connected with the center pin, D³, of the toggle D D', before described, the said toggle as it is straightened by the movement of the pressure-rod D⁴ 95 acting to turn the cam 8, and also the lever E², and move the rod E' and the stop-shoe E to release the dog 6, so that it, acted upon in usual manner by a suitable spring, may be engaged by the wheel D¹¹ and start the rotation of the 100 shaft 4. The under side of the presser-rod D⁴ is connected with one end of the foot-lever F, pivoted at F' by a link. (Shown by dotted lines in Fig. 1.)

When the operator desires to start the machine, it is only necessary to place his foot on the said lever, which effects the elevation of the presser-rod D⁴ in position to have its shoulder 105 110 115 sleeve is moved into its farthest position to the left in the direction of the arrow in Fig. 5, the spline i^5 , when in the said socket, permitting the cam b and hub i^2 to remain at rest 5 while the shaft 4 and sleeve h continue to rotate. When the sleeve h occupies the position shown in Fig. 5, the spline i^5 enters a groove, 113, within the hub of the cam b , thus causing the rotation together of the shaft 4 , 10 to the sleeve, and the said cam.

The flange of the hub h^8 has a side cam, 79, (see Fig. 4,) which at the proper time operates upon the roll m of the lever m' , pivoted at m^2 , causing the slotted upper end of the said lever (shown in dotted lines, Fig. 3, as embracing a pin, 80, of the slide-bar C^2) to move the said slide-bar to the right and place the dog-shoe C' in position to release the dog 2 and permit it to engage the rotating gear B^8 20 and start the shaft B^9 , to set in rotation the usual trimming mechanism, the die-bed spindle being elevated.

The die-bed spindle (see Fig. 3) has attached to it a cylinder, 114, open only at its lower end, 25 it forming what is called a "dash-pot," the said cylinder fitting over the end of a piston, 115, attached to the frame-work, the said cylinder and piston, by the compression of the air therein, serving as a cushion in the descent 30 of the die-bed spindle, thus doing away with the usual rubber packing or cushion usually employed in the McKay and Bigelow machine.

The screw m^6 , connected loosely, as shown 35 in Fig. 13, with the upper end of the spindle 84, to which is joined loosely the usual last-holding slide, A^2 , is screwed into a threaded bushing, 85, provided with a head, m^8 , the said bushing being passed through a spring, 40 m^9 , placed in a chamber in a sleeve, m^{12} , pivoted, as usual, between the forked ends of the walking-beam A' , the said bushing receiving upon its upper end a nut, m^{13} . Normally, the spring m^9 keeps the bushing 85 in the position 45 shown in Fig. 13, the nut m^{13} resting against the upper end of the sleeve m^{12} , so that when pressure is applied to the heel to unite the same to the shoe the bushing is permitted to rise, somewhat compressing the spring m^9 , the 50 spring accommodating itself to slight variations in the height of heels and keeping the outer end of the heel firmly against the nail-block B^3 during the operation of driving the 55 nails, thereby obviating liability of bending the nails should the heels being made be of less than the minimum height for which the machine has been set. The cam b vibrates the lever b' , pivoted at b^2 , and having a roller-stud entering the groove 116 of the said cam. 60 (See Fig. 17.) The slotted upper end of the lever b' engages a pin, b^5 , of the slide-bar b^4 . The slide-bar b^4 has attached to it near its outer end by screw 86 a cross-piece, c^2 , (see Figs. 8, 9, and 10,) the said cross-piece being 65 slotted to receive the fulerum-studs c^4 , on which are mounted the levers or jaws c^5 of the top-lift holder or carrier, the said fulerum-studs

being made adjustable in the said slots by the screws c^3 , and being clamped in adjusted position by the nuts c^6 , the adjustment of the 70 fulerum-studs providing for top lifts of different sizes.

The cross-piece c^2 is bored at its center parallel to the bar b^4 , to receive loosely the front end of a slide-rod, d^8 , fastened by a pin, 117, 75 (see Fig. 9,) to a cam-carriage, d , grooved at its upper side, as shown separately in Fig. 13^a, to fit the lower side of the slide-bar b^4 , which in cross-section is shown as of T shape. The rod d^8 between the front side of the cam-carriage and the cross-piece c^2 , fixed to the bar b^4 , is surrounded by a spiral spring, d^9 , which acts normally to push the carriage backward away from the said cross-head. The rear end of the rod d^8 enters loosely a hole in and is guided 80 by the bearing-block d^4 , attached by suitable screws to the slide-bar b^4 .

The cam-carriage d at its upper side is provided with two diagonally-placed but oppositely-inclined slots, d^5 , (see Figs. 8 and 13^a,) 90 into which enter the roller or other studs, 118, (see dotted lines, Fig. 8,) at or near the rear ends of the jaws or levers c^5 . The bearing-block d^4 receives the screw 202, which serves as the fulerum for the latch 203, (see Fig. 13^a,) 95 having a notch, 204, at its outer or free end, a spring, 205, normally keeping the said latch lifted. As the slide-bar b^4 and cross-piece c^2 are moved back from the nail-box after the jaws have given up a top lift, the spring d^5 100 acts to force the carriage d into its farthest position away from the cross-piece c^2 , keeping the jaws closed; but before the jaws arrive in position to be supplied with a top lift, the carriage strikes at its rear side against the end 105 of a finger, e , having a cam-surface, (see Fig. 12,) and having a shank, e' , entered into a guide, e^2 , where it is acted upon by a spring, e^3 , which normally keeps the finger elevated in position to strike and stop the carriage d . 110

Stopping the carriage while the slide-bar continues to move causes the roller-studs at the inner ends of the jaws or levers c^5 to travel in the cam-grooves of the carriage in such direction as to open the jaws just before their 115 acting faces reach the top lift next to be taken; but as soon as the acting faces of the said jaws reach a position opposite the top lift next to be taken, a lug, d^6 , at the left side of the slide-bar in the backward movement of the 120 latter acts upon the upper cam-shaped or inclined side of the finger e , and pushes the same down against the action of the spring e^3 until the end of the finger is released from the said carriage; but just before the said finger is removed from contact with the said carriage the spring 205, connected, as described, with the latch 203, pivoted at 202, causes the said latch to be elevated, so that its notch 204 engages the rear side of the carriage d , and serves to 125 hold it and keep open the jaws c^5 until they arrive in exactly the proper position for the working-faces of the jaws to grasp the edges of the top lift next to be taken, at which time 130

the latch 203 in the farthest backward movement of the slide-bar b^4 is struck by the stationary stop 206 and is depressed, permitting the spring d^5 to act upon and move the carriage d away from the cross-piece to close the jaws quickly upon the top lift. In this position of the parts the slide-bar b^4 is again moved forward, and the jaws place the top lift held by them between the heel of the shoe and the top-lift plate g^2 , which has been thrown into position by its spring g^5 to cover the nail-box B^3 .

The hopper to contain the top lifts l to be fed to the jaws c^5 is herein shown as composed of two trough-like pieces, $f' f'$, having ears f^2 , which at each side of the hopper are united by rods f^3 , the lower ends of which enter holes in an adjusting-plate, f^4 , (see Fig. 1,) guided in suitable slots or ways of the frame-work, the said plate being made adjustable by the adjusting-screw f^5 in a threaded lug, f^6 , the inner end of the said screw being grooved annularly to engage loosely the upturned end of the said plate. By turning the screw f^5 in one or the other direction the said plate f^4 and the hopper may be adjusted to place the hopper in proper position with relation to the open jaws of the top-lift carrier.

The hopper has at each side a slot, as shown at one side in Fig. 1. The hopper receives within it a weighted follower, f^7 , made as a metal plate, having pins 124 projecting from opposite edges, to enter the slots between the two halves of the hopper. (See Figs. 1 and 18.) This follower acts to force or feed the top lift down in the hopper as one top lift after another is taken from the lower end of the hopper by the top-lift carrier. When the top lifts are being supplied to the hopper, the latter being then temporarily removed from the machine and inverted, the follower acts as a cap for the hopper to enable it to be filled from its lower end, then uppermost. The pins or projections of the follower cannot leave the slots of the hopper because of the shoulders 126. The hopper has at one side a hole to receive a pin, 127, which is inserted after the hopper has been filled, the said pin preventing the escape of the top lifts from this end of the hopper as the hopper is being placed in the machine. The pin 127 is removed after placing the hopper in place in the machine. The slide-bar b^4 is guided in its movements by horizontal ways cut in the block c , attached to the frame-work by bolts 90. The slide-bar (see Figs. 8, 9, and 13^a) is grooved at its sides for some distance to form guides for the auxiliary slide t , the legs 128 of which are placed in the said grooves, the said slide serving as a movable end for the slide-bar b^4 , in order that the effective length of the said bar may be varied, as will be described. As the slide-bar b^4 is moved toward the rear of the machine, the ends of the legs 128 of the auxiliary slide-bar t strike the end of the guide c , and the auxiliary slide is stopped, while the bar b^4 continues to move backward, such movement of the bar b^4 backward leaving the

auxiliary slide-bar t in position below the hopper to sustain the lowermost top lift after the end of the slide b^4 passes to the rear edge of the said top lift, taking with it the jaws or levers c^2 . (See Fig. 8^a.) Sufficient friction is exerted between the legs of the auxiliary slide-bar and the slide-bar b^4 to prevent the movement of the said auxiliary slide-bar t thereon, except when acted upon by a force sufficient to overcome the said friction. As the slide-bar b^4 moves forward with a top lift, the outer downturned end of the bar t meets and is stopped by the rear side of the nail-box B^3 , while the slide b^4 continues to move forward, causing the jaws to carry the top lift into position between the heel and top-lift plate. The lower end of the hopper being open and the pin 127 removed, permits the lowermost one of the pile of top lifts in the hopper to rest at times upon the upper side of the slide-bar b^4 and at other times upon the auxiliary slide t . The auxiliary slide t is pushed into the slide-bar b^4 until the end of the slot thereon (see Fig. 8) meets, or nearly so, the end of the slide-bar b^4 . To prevent the edge of the heel showing a check or open space between the top lift and the heel proper, I have provided the frame-work with a bracket, r , having a paste box or receptacle, r' , and having at its lower end a roll, or it may be a brush, r^2 , or other equivalent device, by which to apply paste, glue, or cement to the upper side of the top lift as the latter is carried forward by the top-lift carrier, the roller being located between the hopper and the nail-box. The top-lift plate g^2 has extended through it a swing-pin, g^3 , provided with a slot, g^4 , to receive the inner end of a clock or other spring, g^5 , the other or outer end of the said spring being made to engage a slot, g^6 , in the top-lift plate. The pin g^3 , upon which the top-lift plate swings, enters the nail-box and is fixed therein in adjusted position by a set-screw, g^7 , the spring normally acting to keep the plate g^2 in position over and to cover the holes in the nail-box.

The frame of the machine has pivoted to it at n a latch, n' , to engage a pin, n^2 , of the toggle A^3 and A^4 in each of its extreme positions, to thus prevent accidental movement of the said toggle. When the die-bed spindle is raised, the latch-lifting rod n^3 , connected to the lever A^8 , is lowered to place the projection n^2 at the side of the said lifting-rod below the lower side of the latch, so that as the die-bed spindle is lowered the said shoulder n^4 in rising will strike the lower side of the latch n' and lift it from engagement with the pin n^2 of the toggle, leaving the latter free to be turned. The latch n' is normally held down by a suitable spring, 207. As the lifting-rod is raised, and after the latch n' has been sufficiently lifted, the cam-lug n^6 on the said lifting-rod n^3 strikes the stop n^7 , causing the lifting-rod to be sprung aside far enough to remove the shoulder n^4 from below the said latch, permitting the spring 207 to depress it to engage the pin n^2 when again brought in

line with one of its notches. The shoe to which the heel is to be attached is placed upon a last, and the last is applied as usual to the slide A². The slide A² is pushed back, to place the shoe 5 in correct position over the nail-box, and the heel, with nails partially driven therein, is applied to the nail-block, the top-lift plate being turned aside, the undriven portion of the nails entering the holes at the upper end of the nail- 10 box, leaving them in position to be acted upon by the ends of the usual drivers as the die-bed spindle has imparted to it its first rise, the usual drivers at that time acting to drive the nails through the heel and into the sole of the 15 shoe, the ends of the nails being, however, left protruding from the small end of the heel to receive the top lift.

The operator to start and effect the rising of the die-bed spindle will place his foot upon 20 the lever F, depressing its outer end far enough to lift the presser-rod D⁴ high enough for its shoulder 109 to be struck by the crank D⁵, which latter moves the presser-rod in the direction to straighten the toggle-joint D D' and 25 lift the die-bed spindle. The nails having been driven, as stated, the cam i³ strikes the roll a' at end of the elbow-lever a², (shown separately in Figs. 7^a and 7^b,) causing the cam-shaped arm a³ thereof to be turned sufficiently far to strike 30 the shoulder 14 of the presser-rod D⁴ and move it backward to break the joint D D', and permit the die-bed spindle to descend; and during this time the cam b in its rotation moves 35 the lever b' to carry forward the slide b⁴ and place a top lift in position above the top-lift plate, which has been turned to cover the nail-holes in the nail-box and rest between it and the end of the heel, and thereafter the cam i⁴, acting upon the lower side of the presser-rod 40 D⁴, lifts the latter, so that its shoulder 109 is again brought in the range of the crank D⁵, to again straighten the toggle-joint and raise the die-bed spindle a second time, it remaining up while the heel is trimmed, in usual manner, 45 and the heel having been trimmed, the cam i³, projecting from the hub i², but at a different angle, acts upon the roll a', it turning the lever a² to again break the toggle, as did the cam i⁴, before described, the breaking of the toggle 50 again effecting the lowering of the die-bed spindle and the backward movement of the presser-rod. As the toggle-joint D D' is straightened, it, through the pin D³ and link 14, connected with the pin 13 of the arm 12, 55 causes the partial rotation of the cam-hub 8 on its fulcrum 9, so that the said cam turns the lever E² and moves the rod E' and stop shoe E to effect the release of the dog 6, the latter engaging the internal teeth of the wheel D¹⁰, 60 causing the shaft 4 to be positively rotated by the dog. The dog 6 is retained in operative engagement with the inner teeth of the wheel D¹⁰ while the shaft 4 makes substantially two rotations, or until the top lift has been attached to the heel and the heel trimmed, at 65 which time the cam i³ operates, as before described, to break the joint in the toggle D D'.

In the revolution of the shaft 4 the cam projection 79 on the hub h³, through the lever m' and the rod C, before described, moves the dog-shoe C' to effect the engagement of the dog 2 with the inner teeth of the wheel B⁸ and rotate the shaft B⁹ one full rotation to thus actuate the trimming mechanism and trim the heel, after which the dog 2 is thrown out of engagement with the teeth of the wheel B⁸ by the spring 92 on the rod C', it operating in opposition to the lever m'. 70 75

In case it should be desired, upon the machine described, to attach heels and omit the usual blind top lift, this may be done by moving the lever h³ in the direction to draw the sleeve h in the direction of the arrow, Fig. 5, until the spline i⁵ enters the chamber 112, such movement leaving the cam b and the hub i² 85 and its cams i³ i⁴ loose or stationary, but the shaft 4 continues to rotate; but to enable the cam h¹⁰ under such conditions to operate to lift the presser-rod D⁴ at the proper times in order to effect the lifting of the die-bed spindle, it is 90 necessary to somewhat change the position of the cam h¹⁰ on or about the shaft 4 and sleeve h, which is done, as before described, by the inclined slot h⁵.

The lever A⁸ has jointed to it the rod w, extended down through an ear, w', and a spring, w², where the rod has attached to it a nut, w'. This rod w is common to United States Patent No. 332,032. 95

The nail-box B³ has rigidly attached to its lower end, as usual, a post, 208, which enters a hole in the top of the die-bed spindle B, the said post at its lower end resting upon a plunger, 209, supported by a spring, 210, the said spring being depressed as the die-bed spindle 105 is raised, the heel resting upon the top of the said nail-box, preventing the nail-box from rising while the nails are being driven therefrom into the heel. The post is as common to the McKay and Bigelow heeling-machine. 110

When applying a top-lift automatically, as herein provided for, the movement of the parts being in rapid succession, it sometimes happens that the nail-block, which must descend by gravity, does not descend as rapidly as the die-bed spindle, and consequently the nail-box is in the way of the top-lift carrier. To obviate this difficulty I have provided the post with a suitable notch or slot, 212, (see Fig. 3^a,) and to co-operate therewith I have provided 120 the die-bed spindle with a latch, 213, herein shown as pivoted near its center and acted upon at its lower end by a spring, 214, which normally keeps the latch in the said notch or slot, so that as the die-bed spindle is lowered 125 positively the post and nail-block will be moved down positively in unison with it, or at the same speed, and cannot hang back, nor can it rebound.

In a machine to apply top lifts automatically at high speed I have found it essential that the breast of the top lift be arrested or stopped at a definite position with relation to the top lift, nail-box, and heel. So to accom- 130

plish this I have herein employed the shoulder 216 on the top-lift plate.

I claim—

1. In a heelng-machine, a slide-bar and pivoted jaws or levers carried thereby to grasp a top lift and means for reciprocating said slide-bar, combined with means, substantially as described, to automatically open and close the said jaws at the proper times, substantially as set forth.

2. In a heelng-machine, a slide-bar and pivoted jaws or levers carried thereby, combined with a carriage having cams or grooves to automatically turn the said jaws or levers on their fulcra, substantially as set forth.

3. The slide-bar, jaws or levers carried thereby, and a sliding carriage to operate the said jaws at the proper times, combined with a latch to hold the carriage in place to keep the jaws open and with a projection to operate the said latch as the slide-bar arrives in position to place the jaws in position to receive and grasp a top lift, substantially as described.

4. The slide-bar, jaws or levers carried thereby, and a carriage to operate the said jaws or levers, combined with a finger to temporarily arrest the movement of the carriage backward with the slide-bar, substantially as described.

5. The slide-bar, jaws or levers carried thereby, and a carriage to operate the said jaws or levers, combined with a finger to temporarily arrest the movement of the carriage backward with the slide-bar and with a latch to engage the carriage after the said finger is disengaged from and releases the said carriage, substantially as described.

6. The slide-bar b^4 and its attached cross-bar and the adjustable studs thereon, combined with the top-lift clamping jaws or levers and with means to open and close the said jaws, substantially as described.

7. The slide-bar b^4 , combined with the auxiliary slide carried by it and with means, substantially as described, to arrest the backward movement of the auxiliary slide as the slide-bar is drawn backward, as and for the purpose described.

8. In a heelng-machine, a hopper to contain and deliver top lifts, one at a time, and a nail-box, combined with a longitudinally-reciprocating top-lift carrier between the said hopper and box and means, substantially as described, for reciprocating said carrier, and automatically-operated jaws or levers having movements toward and from the edges of the top lifts to grasp a top lift and carry it from the said hopper to the said nail-box, substantially as described.

9. In a heel-nailing machine, a hopper to contain and deliver top lifts one at a time, a nail-box, a top-lift plate thereon, and a shoulder to arrest the breast of the top lift, combined with an automatically-operated reciprocating top-lift carrier having jaws, also automatically operated, to take a top lift from the

hopper and carry it in position between the top-lift plate and the shoe to which the top lift is to be attached, substantially as described. 70

10. In a heel-nailing machine, an automatically-reciprocating top-lift carrier provided with jaws or levers to grasp the top-lift, and a nail-block, combined with an auxiliary slide to support the under side of the top lift when placed between the jaws, the said slide being arrested in its movement with the said jaws as the latter place the top lift in position between the nail-box and the heel of the shoe, substantially as described. 75

11. In a heel-nailing machine, the slide-bar b^4 and attached jaws or levers to grasp the edges of and carry a top lift to a nail-box, combined with an auxiliary slide connected loosely to the said slide-bar, the said auxiliary slide 85 being projected beyond the end of the said slide-bar to support the top lift as the same is being placed between the said jaws or levers, substantially as described.

12. In a heel-nailing machine, the walking-beam, its pivoted sleeve m^{12} , the bushing m^8 , its nut m^{13} , and the last-holding spindle with which the said bushing is connected, combined with an interposed spring, to operate substantially as described. 90

13. In a heel-nailing machine, the hopper composed of parts pinned together, slotted at its sides, and having shoulders 126, combined with a follower having pins or projections to enter the said slots to operate substantially as described. 95

14. The hopper and the slide b^4 and means to adjust it, combined with the top lift carrier having jaws or levers to grasp the top lift, substantially as described. 100

15. In a heel-nailing machine, a top-lift carrier having jaws or levers to grasp a top lift and present it in position to be attached to a heel, combined with pasting mechanism to apply paste, cement, or glue to the top lift, substantially as described. 105

16. A hopper to contain lifts and a reciprocating carrier having jaws or levers to grasp the lift, combined with means to apply paste, glue, or cement to a lift preparatory to being applied to a heel, substantially as described. 110

17. The die-bed spindle and the nail-box and its attached post, having a notch or slot, combined with a latch to enter the said notch or slot, to operate substantially as described. 115

18. The die-bed spindle, its attached toggle-link 14, the cam-hub 8, and the lever E^2 , combined with the slide-rod E' and the dog stop-shoe to release the dog 6 and start the shaft 4 when the die-bed spindle is raised, substantially as described. 120

19. The die-bed spindle, its toggle, and the pressure-rod having a shoulder or projection, 14, combined with the lever a^2 , having a projection, a^3 , and with a cam to actuate the said lever and break the toggle and permit the die-bed spindle to descend after the nails have been driven, substantially as described. 125

20. The die-bed spindle, its toggle, and the

pressure-rod provided with a projection, 14, combined with the lever a^2 , having the projection a^3 , and a cam to operate the said lever and actuate the pressure-rod to break the toggle after the heel has been trimmed, substantially as described.

21. In a heel-nailing machine, the shaft 4 and the sleeve splined thereon and slotted, as at h^5 , combined with the hub h^8 and the attached cams i^3 i^4 , to operate substantially as described.

22. In a heel-trimming machine, the shaft 4 and the sleeve splined thereon and provided with a diagonal slot, combined with the hub h^8 and its attached cams i^3 i^4 and b , the latter serving to actuate the top-lift-carrying mechanism, substantially as described.

23. In a heelng-machine, a die-bed spindle, an attached pressure-rod, and the shaft to actuate the pressure-rod to lift the die-bed spindle, combined with the shaft 4, the sleeve keyed to the said shaft, as described, and provided with a spline, and the hub and its attached cams i^3 i^4 , surrounding the said sleeve, the said hub having a chamber, 112, and the intermediate lever, a^2 , to operate substantially as described.

24. In a heelng-machine, the hopper slotted at its sides and the follower or cap f^7 thereon and projections 124, combined with a pin, 127, to hold the lifts in place after the hopper has been filled and until the lifts are to be removed from the hopper, substantially as described.

35 25. The reciprocating slide-bar b^4 and the

auxiliary slide provided with a downwardly-extended lip, combined with the nail-box to arrest the movement of the auxiliary slide in advance of that of the said slide-bar, substantially as described.

26. In a nailing-machine, the lever A' , the toggle-lever A^2 A^3 , and pin n^2 , combined with a latch to engage and hold the said toggle-lever against accidental movement, substantially as described.

27. In a nailing-machine, the lever or beam A' , the toggle-lever A^2 A^3 , and pin n^2 , combined with a latch to engage the said pin and with means, substantially as described, to move the said latch to release the said pin when it is desired to move the said toggle-lever, as set forth.

28. In a heelng-machine, a nail-box, and a support for the shoe to which a heel is to be attached, combined with a movable top-lift carrier composed of jaws, having an automatic positively opening and closing movement to pass around, close upon, and grasp the sides of a top lift, the said jaws being adapted to be positively withdrawn from and release the top lift after the same has been put into position to be blinded upon the heel, substantially as described.

In testimony whereof I have signed my name to this specification in the presence of two subscribing witnesses.

CHARLES W. GLIDDEN.
